UNITED STATES PATENT OFFICE.

JAMES G. BLUNT, OF SCHENECTADY, NEW YORK.

HUB LINER FOR RAILROAD VEHICLES.

Application filed June 8, 1922. Serial No. 568,742.

To all whom it may concern:

Be it known that I, JAMES G. BLUNT, of Schenectady, in the county of Schenectady and State of New York, have invented a certain new and useful Improvement in Hub Liners for Railroad Vehicles, of which improvement the following is a specification.

The object of my invention is to provide simple, inexpensive, and effective means for taking up wear, occurring in service between the outer end of a journal box of a railroad vehicle and the adjoining wheel hub.

The improvement claimed is hereinafter fully set forth.

In the accompanying drawing: Figure 1 is a vertical axial section through a journal box and wheel hub, illustrating an application of my invention in connection therewith; Fig. 2, an outer end view, in elevation, of the journal box; Fig. 3, a horizontal axial section through the journal box and wheel hub; Fig. 4, a view, in perspective, and on an enlarged scale, of the liner; and, Fig. 5, a view, in elevation, of the attaching bolt.

In the practice of my invention, referring descriptively to the specific embodiment thereof which is herein exemplified, two grooves or guide ways, 1^a, 1^b, are formed in the outer end of the journal box, 1, said grooves extending vertically between the top and bottom thereof, on opposite sides of its vertical central plane. One of the sides of each of said guide ways is vertical and at a right angle to the outer end face of the journal box, and the other side is inclined, and also undercut or dovetailed, relatively to said end face.

A liner, 2, is interposed between the journal box and the hub of the adjacent wheel, 4, said liner having tongues, 2^a, of corresponding form and relative location, to the guide ways, 1^a, and fitting neatly therein. The liner is inserted from above, and slid down until it is brought to its proper location on the end of the journal box.

An inwardly turned bearing lug, 2^b, is formed on the top of the liner, and is perforated for the passage of an attaching bolt,

3, having its inner end turned at an angle to its body, so as to form a catch, 3^a, which engages a recess, 1^b, in the vertical central plane of the outer end of the journal box. The bolt, 3, is screw threaded at its outer end portion, and is provided with a nut, 3^b, which may be turned to a bearing on the lug, 2^b, of the liner, thereby maintaining the liner in connection with the journal box, and enabling it to be drawn to a tighter bearing, as may, from time to time, become necessary to take up wear between the liner and the wheel hub.

It will be seen that my invention is readily applicable in connection with journal boxes of the various types of present practice, at comparatively slight cost, and that, in operation, wear of the outer end surface of the journal box and the adjacent wheel hub, may be taken up whenever necessary or desirable, by adjustment of the nut of the attaching bolt.

I claim as my invention and desire to secure by Letters Patent:

1. The combination, with a journal box and a wheel and axle of a railroad vehicle, of a liner, interposed between the journal box and the wheel hub; means for connecting said liner adjustably to the journal box; and means for effecting vertical adjustment of said liner, relatively to the journal box.

2. The combination, with a wheel and axle of a railroad vehicle, of a journal box having vertical guide ways in its outer end; a liner, interposed between said journal box and the hub of the wheel, and having vertical tongues engaging the journal box guide ways; and an attaching bolt, connecting said liner adjustably to the journal box.

3. The combination, with a wheel and axle of a railroad vehicle, of a liner, fitting against the hub of the wheel, and having vertical tongues on its inner side, each of which tongues has an inclined side; a journal box, having guide ways engaged by said tongues; an attaching bolt, adjustably connecting the liner and the journal box; and a nut engaging said bolt and bearing on the liner.

4. The combination, with a wheel and

axle of a railroad vehicle, of a liner, fitting against the hub of the wheel, and having a horizontal bearing lug on the top of its inner side, and vertical tongues, each of which has an inclined side; a journal box, having guide ways engaged by said tongues; an attaching bolt, engaging a recess in the

journal box, and passing through the bearing lug of the liner; and a nut, engaging said bolt and abutting on said bearing lug. 16

JAMES G. BLUNT.
